V. J. BUCHANAN

HAT OR CAP SWEATBAND SHIELD OR PAD

Filed April 3, 1922

UNITED STATES PATENT OFFICE.

VERNON JAMIESON BUCHANAN, OF NEWPORT, RHODE ISLAND.

HAT OR CAP SWEATBAND SHIELD OR PAD.

Application filed April 3, 1922. Serial No. 549,098.

To all whom it may concern:

Be it known that I, VERNON JAMIESON BUCHANAN, a citizen of the United States, residing at Newport, in the county of Newport and State of Rhode Island, have invented certain new and useful Improvements in Hat or Cap Sweatband Shields or Pads, of which the following is a specification.

10 The invention relates to a hat or cap sweat band attachment and more particularly to the class of detachable shields or pads for use with hat or cap sweat bands.

15 The primary object of the invention is the provision of a shield or pad of this character wherein it can be detachably fastened about the sweat band of a cap or hat, irrespective of the nature or style of the head-gear and when in position will afford comfort to the wearer of the head-gear, as it will overcome unpleasantness to a wearer, who tips the hat or cap back from the forehead, especially during warm weather, as the shield or pad will absorb perspiration or 20 moisture during the wearing of the head-gear and thereby eliminate the usual skin eruptions when the sweat band contacts with the head of the wearer.

Another object of the invention is the provision of a shield or pad of this character wherein the construction thereof is novel in form, so that it can be readily and easily applied to sweat bands for use and removed at will, especially when the same becomes 30 soiled, so that it can be laundered, thereby rendering the same sanitary and of appealing comfort when in use.

A further object of the invention is the provision of a shield or pad of this character, which will eliminate, when attached to a sweat band of a hat or cap, the discoloring of such sweat band and the distortion thereof and will assure comfort to the wearer of the hat or cap, as it will eliminate to a 40 marked degree the moistening of the sweat band from perspiration while the hat or cap is in use.

A still further object of the invention is the provision of a shield or pad of this character, which is extremely simple in construction, readily and easily applied to or removed from a sweat band of a head-gear, thoroughly reliable and efficient in its purpose and inexpensive to manufacture.

55 With these and other objects in view, the invention consists in features of construc-

tion, combination and arrangement of parts, as will be hereinafter more fully described, illustrated in the accompanying drawings and pointed out in the claim hereunto appended.

In the accompanying drawings—

Fig. 1 is a perspective view of a hat and sweat band, showing the shield or pad applied in position to the sweat band and constructed in accordance to the invention,

Fig. 2 is a fragmentary, vertical, sectional view through the hat and shield or pad with one end portion of the pad curled outwardly and upwardly for exhibiting fasteners therefor,

Fig. 3 is a plan view of the shield or pad removed from the sweat band.

Similar reference characters indicate corresponding parts throughout the several views in the drawings.

Referring to the drawings in detail, A designates generally a hat having therein the usual sweat band B, the hat of the type shown in Figs. 1 and 2 of the drawings being merely illustrative of the application of use of the shield or pad, hereinafter fully described.

The shield or pad comprises a two-ply fabric constituting an elongated body 5 having the rounded ends 6, the plies of material being preferably of fabric, yet the same may be made from any other material, and the marginal edges of these plies are hemmed and stitched as at 7 for uniting the plies. 80 It is of course understood that the body 5 may be of the required length and width and on one side thereof, near the longer edges are suitably fastened male and female fastening members 8 and 9, respectively, the same in this instance being of the ball and socket snap fasteners.

Formed in the sweat band B on each side of the hat is a hole or opening 10 of a size corresponding to the character of the fastener on the shield or pad and the latter when applied to said sweat band B is folded on itself to bridge the sweat band throughout the front portion of the hat A, while one stretch of the shield or pad will lie between the crown of the hat and the sweat band and the other stretch of said shield or pad will lie against the outer face of the sweat band, so as to contact with the forehead of the wearer of the hat to absorb perspiration and to keep the same off of the sweat band B as will be clearly apparent.

The shield or pad can be readily reversed on the sweat band B and as is obvious may be detached at will, so when it becomes soiled, it may be laundered, thereby rendering it sanitary and devoid of unsightly appearance.

When the shield or pad is applied to the sweat band, the male member 8 of the fastener projects through the hole 10 in the sweat band and engages in the female member 9 of the fastener to secure the shield or pad fixed upon the sweat band.

From the foregoing, it is thought that the construction and manner of application and use of the shield or pad will be clearly understood, and, therefore, a more extended explanation has been omitted.

What is claimed is:—

A sweat band attachment for hats comprising a flexible substantially elongated rectangular body folded at its longitudinal center upon itself to provide an outer and

an inner complemental fold and adapted to straddle a sweat band from the upper edge thereof, each of the folds of said body of 25 a width to extend in proximity to the lower secured edge of the sweat band when said body is mounted on the latter, a male fastener member secured to the outer fold of said body near each end and in proximity to 30 the free longitudinal edge of said outer fold and adapted to extend through the sweat band when said body is mounted on the latter, and female fastener members positioned to oppose the male fastener members and 35 each secured to the inner fold of said body near each end thereof and in proximity to the free longitudinal edge of said inner fold, said male fastener members engaging with said female fastener members for detachably 40 coupling said body to the sweat band.

In testimony whereof, I affix my signature hereto.

VERNON JAMIESON BUCHANAN.
